(57) **CLAIM**

The ornamental design for an implant for pelvic organ prolapse as shown and described.

DESCRIPTION

FIG. 1 is a perspective view of an implant for pelvic organ prolapse, showing our new design;

FIG. 2 is a top plan view thereof;

FIG. 3 is a bottom plan view thereof;

FIG. 4 is a left side plan view thereof;

FIG. 5 is a right side plan view thereof;

FIG. 6 is a front elevational view thereof; and,

FIG. 7 is a rear elevational view thereof.

The broken lines shown in the figures depict portions of the implant for pelvic organ prolapse that form no part of the claimed design.
